(57) **CLAIM**

The ornamental design for a conversion cable, as shown and described.

DESCRIPTION

FIG. 1 is a perspective view of the top, front and one end of a conversion cable showing my new design;

FIG. 2 is an end elevational view of said one end thereof;

FIG. 3 is an end elevational view of an opposite end thereof;

FIG. 4 is a front elevational view thereof;

FIG. 5 is a top plan view thereof;

FIG. 6 is a side elevational view of an opposite side thereof; and,

FIG. 7 is a bottom plan view thereof.

The elements shown in phantom lines do not form any part of the claimed design.
